SWIMMER'S LIFE SAVING BELT

Filed Sept. 9, 1929

INVENTOR
Joseph S. WOLLK
BY *John Holachek*
ATTORNEY

UNITED STATES PATENT OFFICE

JOSEPH S. WOLK, OF NEW YORK, N. Y.

SWIMMER'S LIFE-SAVING BELT

Application filed September 9, 1929. Serial No. 391,199.

This invention relates to new and useful improvements in a swimmer's life saving belt.

The invention has for an object the provision of a device of the class mentioned which is of simple durable construction, dependable in use and efficient in action, and which can be manufactured and sold at a reasonable cost.

The invention proposes a belt of the type 10 mentioned consisting of a plurality of containers with reduced inlets connected with an air supply strap having a mouth piece for manual inflation, and a means for attaching the containers to each other and upon a person. It is proposed to so construct the containers and the air supply strap so as to be inflatable and maintain the inflation without 15 actual valves. These parts should be so arranged to have an inherent valve action.

20 The valve action referred to should be arranged independently for each of the containers so that in the event of rupture of one, all of them will not deflate. The valve action is primarily accomplished by providing a 25 small passage for air and composed of flexible material rubberized for normally closing the passage.

For further comprehension of the invention, and of the objects and advantages there- 30 of, reference will be had to the following description and accompanying drawings, and to the appended claims in which the various novel features of the invention are more particularly set forth.

35 In the accompanying drawing forming a material part of this disclosure:

Fig. 1 is a perspective view of a person provided with the safety belt.

40 Fig. 2 is a developed view of the belt, per se. Fig. 3 is an end elevational view looking in the direction of the arrows 3—3 of Fig. 2.

Fig. 4 is an enlarged horizontal sectional view taken on the line 4—4 of Fig. 3.

45 Fig. 5 is a fragmentary enlarged horizontal sectional view taken on the line 5—5 of Fig. 2.

Fig. 6 is an enlarged vertical sectional view taken on the line 6—6 of Fig. 2.

Fig. 7 is a fragmentary enlarged sectional view taken on the line 7—7 of Fig. 2.

50 Fig. 8 is a fragmentary enlarged elevation-

al view looking in the direction of the line 8—8 of Fig. 1.

Fig. 9 is a fragmentary enlarged elevational view of a portion of two of the containers shown in Fig. 2 with the top straps 55 removed.

Fig. 10 is an enlarged elevational view of a portion of Fig. 2.

Fig. 11 is a fragmentary view of a portion of Fig. 2 but constructed according to modified form.

Fig. 12 is an enlarged sectional view taken on the line 12—12 of Fig. 2.

The reference numeral 14 indicates generally a person having a swimmer's life saving belt 15 applied. This belt encircles the waist portion and consists of a plurality of air containers 16 with reduced inlets 17 connected with an air supply strap 18 having a mouth piece 19 for manual inflation, a means 20 for attaching the containers to each other, and another means 21 for attaching the containers upon a person.

Each of the containers consists of a pair of superimposed congruent sheets of cloth 22 75 rubberized on their inner sides and hermetically sealed along all edges except at small portions of one of the edges of each sheet respectively, which portions accommodate the said reduced inlet 17.

The said air supply strap 18 consists of a pair of superimposed congruent sheets of cloth 23 rubberized on their inner sides and hermetically sealed along all edges except at one end which is provided with an inlet tube constituting the said mouth piece 19, and at portions along its length where the reduced portions 17 of the containers connect. This arrangement provides an air passage 90 extending the full length of the air supply strap and connecting with the interior of the containers 16.

The said reduced inlet portions 17 of each of the containers consist of the sheets of the container flat against each other and are engaged between the material 22 of the air supply strap. In Fig. 7 the air passage between the reduced inlet 17 and the sheets 23 is highly exaggerated. In reality they touch each other and open slightly only upon the forcing 100

of air through these parts. Immediately thereafter they touch each other again and form a valve action for retaining the air within the containers.

5 The said means 20 for attaching the containers to each other consists of forming the adjacent edges of each of the containers with eye openings 24 and then connecting these openings with a lace 25. This arrangement permits the distance between the containers to be 10 adjusted. The means 21 for attaching the containers upon a wearer consist of upper and lower straps 26 on each of the containers and attached intermediate of their ends. This 15 permits the ends of the straps to be free, and adjacent ends of adjacent straps are formed with eye openings 27, and lace 28 is engaged between these openings for connecting the straps.

20 The outer ends of the upper and lower straps 26 of the first and last containers 16 are attached upon vertical dowels 29. These dowels are adjustably connected with the vertical edges of the container by laces 30. A 25 strap 31 with a buckle 32 is attached upon one of the dowels and the buckle is engageable with another strap 33 attached upon the other of the dowels which completes the means for attaching the belt upon a person.

30 In Fig. 4, the section of the top strap 26 discloses that this strap is made from sheets of cloth with rubber therebetween. Adjacent edges of each of the containers are reinforced with strips 34 secured on their inner sides. This is clearly shown in Fig. 5 which represents a section of adjacent containers in Fig. 2. The air passage strap 18 has been defined with a central air passage indicated in Fig. 12 by reference numeral 35. This air 40 passage is highly exaggerated in the drawing but serves to illustrate its arrangement.

Because of the length of the air passage strap, it has been found necessary to insert an intermediate passage tube 36 for holding a 45 portion of the passage open so that it is not very difficult to inflate the device. The passage tube 36 extends for a short distance between two of the reduced inlets 17 of adjacent containers. After the device has been inflated, the air passage strap 18 is turned upwards on the inner side of the belt as illustrated in Figs. 1 and 8 so as to be clamped against the person. In this position each of the bent reduced inlets 17 insures against deflation of the air containers.

In the modified form of the device illustrated in Fig. 11, an air supply strap 18' has been illustrated connecting with the central portions of the containers 16 instead of with 50 the edges as illustrated and described in the preferred construction. In other respects this belt is similar, and corresponding parts may be recognized by corresponding numerals. The valve action in this case is obtained 55 when the belt is secured about a wearer which

firmly forces the passage within the air supply strap closed.

In operation of the device, it may be inflated manually by blowing through the mouth piece 19. The air forces the passage 70 35 momentarily open and also forces the passages through the reduced inlets 17 open so that the air may enter the containers. Immediately upon the ceasing of blowing, these passages close and particularly the reduced inlets 17 tend to bend for further insuring the closing of the passage of air and the locking of the air within the containers. After the containers have been fully inflated, the air supply strap is bent upwards against 80 the inner side of the belt and in this condition an air tight construction is obtained. Particular attention is called to the rubber lining of the containers and the air passage strap which 85 accomplishes the air tight valve action discussed.

While I have shown and described the preferred embodiment of my invention, it is to be understood that I do not limit myself to the precise construction herein disclosed and the right is reserved to all changes and modifications coming within the scope of their invention as defined in the appended claims.

Having thus described my invention, what I claim as new, and desire to secure by United States Letters Patent is:—

1. A swimmer's life saving belt comprising a plurality of air containers connected with an air supply strap having a mouth piece for manual inflation, said air supply strap consisting of a pair of superimposed sheets of cloth material rubberized on their inner sides and hermetically sealed along the edges, means for attaching the containers to each other, and means for holding them on the body of a wearer.

2. A swimmer's life saving belt comprising a plurality of air containers connected with an air supply strap, said air supply strap consisting of a pair of superimposed sheets of cloth material rubberized on their inner sides and hermetically sealed along the edges, means for attaching the containers to each other, and means for holding them on the body of a wearer.

3. A swimmer's life saving belt comprising a plurality of air containers being formed with reduced inlets connected with an air supply strap having a mouth piece for manual inflation, said air supply strap consisting of a pair of superimposed sheets of cloth material rubberized on their inner sides and hermetically sealed along the edges, means for attaching the containers to each other, and means for holding them on the body of a wearer.

4. A swimmer's life saving belt comprising a plurality of air containers being formed with reduced inlets, said containers consisting of a pair of superimposed congruent

sheets of cloth rubberized on their inner sides and hermetically sealed along all the edges except for a small portion which constitutes said reduced inlet and each connected with
 5 an air supply strap having a mouth piece for manual inflation, said air supply strap consisting of a pair of superimposed sheets of cloth material rubberized on their inner sides and hermetically sealed along the edges,
 10 means for attaching the containers to each other, and means for holding them on the body of a wearer.

5. A swimmer's life saving belt comprising a plurality of air containers connected with
 15 an air supply strap having a mouth piece for manual inflation consisting of a tube inserted in the end of the strap, said air supply strap consisting of a pair of superimposed sheets of cloth material rubberized on their inner
 20 sides and hermetically sealed along the edges, means for attaching the containers to each other, and means for holding them on the body of a wearer.

6. A swimmer's life saving belt comprising a plurality of air containers connected with an air supply strap having a mouth piece for manual inflation, said air supply strap consisting of a pair of superimposed sheets of cloth material rubberized on their inner sides
 30 and hermetically sealed along the edges, and having a small tube intermediate of its ends for maintaining a portion of its passage open, means for attaching the containers to each other, and means for holding them on the
 35 body of a wearer.

7. A swimmer's life saving belt comprising a plurality of air containers connected with an air supply strap having a mouth piece for manual inflation, said air supply strap consisting of a pair of superimposed sheets of cloth material rubberized on the inner sides and hermetically sealed along the edges, means for attaching the containers to each other, consisting of laces engaged thru eye
 40 openings of adjacent edges of adjacent containers, and means for holding them on the body of a wearer.

8. A swimmer's life saving belt comprising a plurality of air containers connected with
 50 an air supply strap having a mouth piece for manual inflation, said air supply strap consisting of a pair of superimposed sheets of cloth material rubberized on their inner sides and hermetically sealed along the edges,
 55 means for attaching the containers to each other, and means for holding them on the body of a wearer, consisting of upper and lower straps secured intermediate of their ends on the containers, laces connecting the
 60 straps, a dowel rod attached between the free ends of the upper and lower straps, and central straps with a buckle attached on the dowel rods.

9. A swimmer's life saving belt comprising
 65 a plurality of air containers connected with

an air supply strap having a mouth piece for manual inflation, said air supply strap consisting of a pair of superimposed sheets of cloth material rubberized on their inner sides and hermetically sealed along the edges,
 70 said air supply strap connected with the center portions of one of the sides of each container, means for attaching the containers to each other, and means for holding them on the body of a wearer.

In testimony whereof I have affixed my signature.
